BEER CAN

Kenneth E. Siegler, 1004 S. Pine St.,
Port Angeles, Wash. 98362

Filed Apr. 20, 1970, Ser. No. 22,519

Term of patent 14 years

Int. Cl. D9—07

U.S. Cl. D9—216

FIG. 1 is a top perspective view of a beer can showing my new design;

FIG. 2 is a side elevational view thereof;

FIG. 3 is a top plan view thereof; and

FIG. 4 is a bottom plan view thereof.

I claim:

The ornamental design for a beer can, substantially as shown.
